UNITED STATES PATENT OFFICE.

EDMUND E. TAEUBERT, OF LOS ANGELES, CALIFORNIA.

ELECTRIC SAD-IRON.

1,114,413.

Specification of Letters Patent.

Patented Oct. 20, 1914.

Application filed August 21, 1913. Serial No. 786,018.

To all whom it may concern:

Be it known that I, EDMUND E. TAEUBERT, a citizen of the United States, residing at Los Angeles, in the county of Los Angeles and State of California, have invented certain new and useful Improvements in Electric Sad-Irons; and I do hereby declare the following to be a full, clear, and exact description of the invention, such as will enable others skilled in the art to which it appertains to make and use the same.

This invention comprehends improvements in electric sad irons and has for one of its objects the provision of a novelly formed iron of extremely simple and practical construction and having a peculiarly formed heating element.

Another and more specific object of the invention resides in the provision of a heating element especially adapted for electrically heated sad irons but which may be used for other purposes by merely changing the shape thereof. This heating element is composed of a sheet of insulating material such as mica having a row of perforations spaced from the edge thereof and a resistance element extended through said perforations and across the edge of the sheet.

A still further object of the invention resides in the provision of a sad iron having a body formed of upper and lower sections, said sections being recessed upon their opposed sides to form a channel in which the resistance coil forming a part of the heating element is disposed.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a side elevation of my improved electrically heated sad iron, Fig. 2 is a top plan view of the lower body section, showing the heating element positioned thereon, Fig. 3 is a vertical transverse section taken on the plane of line 3-3 of Fig. 1, Fig. 4 is a fragmentary view of the rear end of the iron shown partly in section and partly in elevation, Fig. 5 is a bottom plan view of the top section of the body, Fig. 6 is a top plan view of the casing, and, Fig. 7

is a section taken on the plane of line 7-7 of Fig. 1, the plug being removed.

Referring in detail to the drawings by numerals, 10 designates the lower section and 11 the upper section of the sad iron body, said body being of the usual triangular shaped formation having forwardly converging somewhat convex sides and a straight rear face. The lower section 10 has formed in its upper face a channel or recess, generally designated 12, which is essentially semicircular in cross section and which comprises the converging side portions 13 and the rear portion 14. This channel is similar in shape to the lower section and is spaced a slight distance from the edge thereof. The side and rear faces of the lower section are recessed, as indicated by the numeral 15, for a purpose to be hereinafter explained and serve to form what might be termed a rib or flange 16 between the channel 12 and recess 15.

The top section 11 is formed upon its under side with a channel or recess 17 which is opposed to the channel 12 and which forms therewith a housing which is essentially circular in cross section. The upper section is somewhat smaller than the lower section and does not extend outwardly beyond the flange 16 or rib 16, as is clearly shown in Figs. 3 and 7. This section is formed upon its upper side adjacent its rear edge with a projection 18 through which the terminal members 19 and 20 extend. The lower enlarged ends of the terminal members are positioned within the openings 21 and are constructed so that the ends of the resistance element to be described later, may be easily attached thereto.

The heating element is secured between the sections of the body and comprises a sheet of insulating material 22, preferably mica, which is of such size and shape as to extend into the housing formed by the channels 12 and 17. The insulating sheet is formed adjacent its side edges with a series of holes or perforations 23 and the resistance element 24 in the form of a spiral coil of wire, is extended through said openings and across the edges of the sheet, as clearly shown in Fig. 2. The mica sheet is of such size and shape and the perforations are so positioned therein as to dispose the resistance coil centrally between the channels 12 and 17, as shown in Figs. 3 and 7. The ends of the resistance coil are connected to the inner extremities of the terminal members

19 and 20. It will be apparent that my heating element may be adapted for use in different ways from that shown, such for instance, as in an electrically heated stove.

5 A shell or casing 25 fits over the top section 11 and rests upon the shoulder 26 formed by the recess 15. Studs 27 are threaded into the top of the lower section 10 and extend through the upper section 11, 10 the casing 15 and handle 28. Nuts 29 hold the section 11 against the heating element and the nuts 30 secure the handle in position. The casing is formed with an opening 31 through which the projection 18 existing 15 tends.

32 designates a plug by means of which the resistance coil may be thrown into and out of circuit.

An angular rest 33 formed of a metallic 20 rod is secured within the openings 34 formed in the rear face of the body section 10.

From the foregoing description taken in connection with the accompanying drawing, it will be seen that I have provided a very 25 simply constructed electrically heated sad iron, which may be easily assembled, and which is provided with a novelly constructed heating element having a resistance coil disposed in channels formed in the opposed 30 faces of the upper and lower body sections.

As before stated, the heating element is not limited to use in connection with a sad iron but may be used in connection with various other objects.

35 It is to be understood that while I have shown and described the preferred embodiment of my invention, I do not wish to be limited to this exact construction, combination, and arrangement of parts, but may 40 make such changes as will fall within the spirit and scope of the invention as defined by the appended claims.

Having thus described my invention, what I claim is:—

45 1. A heating element comprising a sheet of insulating material formed with a single series of perforations, and a resistance member extended through said perforations and across the edge of the sheet, said resistance 50 member only embracing that portion of the sheet lying between the perforations and the edge of the sheet.

55 2. A heating element comprising a sheet of mica having a series of perforations formed therein adjacent the edge thereof,

and a resistance member formed of a spiral coil of wire, threaded through the perforations and extended across the edge of the sheet, said resistance member embracing only that portion of the mica sheet lying between the perforations and the edge of said sheet, whereby the remainder of the sheet may be engaged with a supporting member.

3. In a sad iron, a body formed of upper and lower sections, the opposed faces of said sections being formed with opposed channels, and a heating element comprising a sheet of non-conducting material positioned between said sections and extending partly across the channels, the sheet being formed with a series of perforations disposed within the channels, and a resistance member threaded through said perforations and across the edge of the sheet.

4. In a sad iron, a body formed of an upper and lower section with the opposed faces of said sections being formed adjacent their edge with opposed channels, a sheet of mica positioned between the sections and extending partly across the channels formed therein, the sheet being formed adjacent its edges with a series of perforations, and a resistance element formed of a spiral coil of wire, said element being threaded through the perforations and extending across the edges of the sheet.

5. A sad iron comprising a body formed of an upper and a lower section, the lower section having formed in its upper face a channel, the channel conforming to the shape of the section, the lower face of the upper section being formed with a channel opposed to the first mentioned channel, an insulating sheet disposed between the sections and extending partly across the channels, said sheet being formed adjacent its edges with a series of perforations disposed within the channels, a resistance element formed of a spiral coil of wire and mounted upon said insulating sheet, the coil extending through the perforations and across the edge of the sheet, and a pair of terminal members carried by the upper section to which the ends of the coil are connected.

In testimony whereof I affix my signature 105 in presence of two witnesses.

EDMUND E. TAEUBERT.
